BACKFIRE RELEASE

Frank T. Christian, Elmira, N. Y., assignor to
 Eclipse Machine Company, Elmira, N. Y., a
 corporation of New York

Application November 30, 1931, Serial No. 578,180

8 Claims. (Cl. 290—38)

This invention relates to a back-fire release for internal combustion engines and more particularly to a device for temporarily rendering inoperative an automatic starting mechanism 5 for internal combustion engines in case the engine back-fires.

It has been found desirable in connection with automatic starting mechanism for internal combustion engines to provide means for preventing 10 engagement of the starting mechanism while the engine is rotating backward as in case of back-fire. It is further desirable to delay the reengagement of the starting mechanism until the engine has ceased rocking and has come completely to rest, in order to prevent engagement 15 of the starting mechanism while the engine is rotating or rocking backward.

It is an object of the present invention to provide a novel device for rendering an automatic 20 starting mechanism inoperative as a result of backward rotation of the engine.

It is another object to provide such a device 25 which provides a time delay after such backward rotation ceases before reactivation of the starting mechanism.

It is a further object to provide such a device 30 which is adapted for use with commercial forms of automatic starting mechanism or with known forms of relay-operated starting switches.

35 Further objects and advantages will be apparent to those skilled in this art from the following description taken in connection with the accompanying drawing in which the figure is a semi-diagrammatic showing of a preferred form of the invention.

In the drawing there is illustrated an electrical starting system for an internal combustion engine, not illustrated, comprising a battery 1 grounded at 2 and connected by a lead 3 to an 40 automatic starting mechanism indicated generally by numeral 4. The automatic starting mechanism includes a starting switch 5 which is connected by a lead 6 to a starting motor SM which is grounded at 7 whereby closure of the 45 switch 5 completes the starting circuit and causes cranking of the engine.

The switch 5 is adapted to be operated magnetically by suitable means such as a solenoid 8 which is actuated by a control circuit including a 50 battery switch 9 which may also be the ignition switch of the engine, leads 11, 12 and 13, contacts 14, spring strip 15, and ground 16. Leads 11 and 12 are normally connected by means of a thermostatic element 17 connected at 18 to the 55 lead 11, and having a contact 19 at its opposite end

arranged to engage a contact 21 connected to the lead 12. It will thus be seen that closure of the switch 9 when the parts are in normal position will cause actuation of solenoid 8 to close the starter switch 5.

According to the present invention means are provided for opening contacts 19, 21 of the control circuit in case of backward rotation of the engine and for maintaining said contacts open for a predetermined time after backward rotation ceases. For this purpose, a movable thrust member 22 is arranged in position to engage the thermostatic element 17, and is mounted on a flexible diaphragm 23 which is subjected, as indicated, to the pressure within an element 24 of the fuel intake system of the engine such as the intake manifold. The member 22 is further provided with an electrical contact 25 adapted to engage a contact 26 on the thermostatic element 17, and since the member 22 is grounded on the intake manifold, as indicated at 27, closure of contacts 25, 26 causes a circuit to be established from the lead 11 through the thermostatic element 17 to the ground whereby the thermostatic element is heated. The thermostatic element is arranged so that an increase of temperature thereof causes control contact 19 to move away from the fixed contact 21.

In the operation of the device, closure of the switch 9 will under normal conditions cause actuation of the solenoid 8 to close the starting switch 5 as above set forth. However, if the engine should back-fire, pressure in the intake manifold 24 causes the diaphragm 23 to raise the thrust member 22, opening control contacts 35 19, 21 and closing the heater contacts 25, 26 whereby the thermostatic element 17 is immediately heated by the current traversing contacts 25, 26 to the ground at 27.

When the backward rotation of the engine ceases, the pressure in the intake manifold 24 is dissipated, allowing the diaphragm 23 and thrust member 22 to return to their normal positions. The thermostatic element 17, will, however, not close control contacts 19, 21 until said element 45 has cooled down, thereby introducing a time delay for the reactivation of the starting switch in order to ensure that the engine comes completely to rest before such reactivation.

Although but one embodiment of the invention has been shown and described in detail, it will be understood that various other embodiments are possible and certain changes may be made in the construction and arrangement of the parts without departing from the spirit of 55

the invention as defined in the claims appended hereto.

What is claimed is:—

1. Starting mechanism for internal combustion engines including a magnetically operated starting switch, a control circuit for said starting switch including a pair of contacts, means responsive to backward rotation of the engine for opening said contacts, and means for delaying closure of the contacts for a time interval after return of said opening means to normal position. 5
2. Starting mechanism for internal combustion engines including a magnetically operated starting switch, a control circuit for said starting switch including a pair of contacts, means responsive to backward rotation of the engine for opening said contacts, and the mostatic means actuated by said opening means for delaying closure of the contacts for a predetermined time after return of said opening means to normal position. 10
3. In combination with an internal combustion engine having a fuel intake system, an electrical starting system therefor including a motor and a starting switch, manually controllable means for closing said starting switch, means responsive to pressure in the fuel intake system for rendering said closing means inoperative, and thermostatic means for delaying the reoperation of said closing means for a predetermined time after the dissipation of said pressure. 15
4. In combination with an internal combustion engine having a fuel intake system, an electrical starting system therefor, including a motor and a starting switch, magnetic operating means for the starting switch, manually controllable means for energizing said magnetic means, means responsive to pressure in the fuel intake system for rendering said energizing means inoperative, and thermostatic means activated by the pressure responsive means for delaying the reoperation of said energizing means for a predetermined time after the dissipation of said pressure. 20
5. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact and means responsive to pressure in the intake system of the engine for causing the thermostatic element to be heated to open said contacts. 25
6. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact and means responsive to pressure in the intake system of the engine for opening said contacts and causing the thermostatic element to be heated to maintain the contacts open for a predetermined time after the intake pressure has been dissipated. 30
7. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact, said thermostatic element being arranged to open said control contacts responsive to a rise in temperature, a heater circuit for the thermostatic element including a contact carried thereby, a movable element having a contact arranged to cooperate with the heater contact and complete the heater circuit, and means responsive to pressure in the intake system of the engine for closing said heater contacts. 35
8. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact, said thermostatic element being arranged to open said control contacts responsive to a rise in temperature, a heater circuit for the thermostatic element including a contact carried thereby, a movable element having a contact arranged to cooperate with the heater contact and complete the heater circuit, and means responsive to pressure in the intake system of the engine for closing said heater contacts and opening said control circuit contacts. 40
9. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact and means responsive to pressure in the intake system of the engine for causing the thermostatic element to be heated to open said contacts. 45
10. In combination with an internal combustion engine having a fuel intake system, an electrical starting system therefor including a magnetic starting switch relay, a control circuit for said relay including a thermostatic element, a movable contact carried thereby, and a fixed contact normally engaged by the movable contact and means responsive to pressure in the intake system of the engine for opening said contacts and causing the thermostatic element to be heated to maintain the contacts open for a predetermined time after the intake pressure has been dissipated. 50
